UNITED STATES PATENT OFFICE

129,546

DESIGN FOR A KEY

Charles L. Ragot, New York, N. Y.

Application May 11, 1940, Serial No. 92,312

Term of patent 3½ years

To all whom it may concern:

Be it known that I, Charles L. Ragot, a citizen of the United States, residing at New York, in the county and State of New York, have invented a new, original, and ornamental Design for a Key, of which the following is a specification, reference being had to the accompanying drawing, forming part thereof.

Fig. 1 is a side elevational view of a key showing my new design; and

Fig. 2 is an edge elevational view thereof.

It is contemplated that the article may also be used as an ornament.

I claim:

The ornamental design for a key, as shown.

CHARLES L. RAGOT.
